(57) **CLAIM**

The ornamental design for a handle for a water bottle, as shown and described.

DESCRIPTION

FIG. 1 is an upper front perspective view of the design;

FIG. 2 is a lower front perspective view of the design;

FIG. 3 is a front elevation view of the design;

FIG. 4 is a rear elevation view of the design;

FIG. 5 is a right side elevation view of the design;

FIG. 6 is a left side elevation view of the design;

FIG. 7 is a bottom plan view of the design; and,

FIG. 8 is a top plan view of the design.

The broken lines depict portions of the handle for a water bottle that form no part of the claimed design.

1 Claim, 8 Drawing Sheets
